UNITED STATES PATENT OFFICE.

NATHAN COHEN, OF SWINDON, ENGLAND, ASSIGNOR OF ONE-HALF TO FRANK BOWERMAN, OF SWINDON, ENGLAND.

DENTAL SUCTION-DISK.

1,243,386.

Specification of Letters Patent. Patented Oct. 16, 1917.

Application filed October 5, 1915. Serial No. 54,166.

To all whom it may concern:

Be it known that I, NATHAN COHEN, a subject of the King of Great Britain, residing in Swindon, in the county of Wiltshire, 5 England, have invented certain new and useful Improvements in Dental Suction-Disks, of which the following is a specification.

This invention relates to improvements in 10 dental suction disks of soft rubber. As distinguished from known disks of this type, a disk made in accordance with the present invention is formed upon a soft metal mold upon which it is partly vulcanized; the disk 15 together with the mold thereon being issued to the dentist ready for application to the denture in the ordinary manner. The soft-metal mold serves to protect the disk and facilitates its application to the denture, being removed after the vulcanization of the 20 denture has been effected.

In the accompanying drawings:

Figure 1 is a top plan view of one form 25 of suction made according to this invention, designed for use upon an upper denture.

Fig. 2 is a section thereof on the line 2—2 of Fig. 1.

Fig. 3, is a top plan view of a form of suction designed for use upon a lower 30 denture.

Fig. 4, is a section of the structure shown in Fig. 3 taken on the line 4—4 thereof.

Fig. 5, is a bottom plan view of a lower 35 denture showing my improved form of soft suctions therein; and

Fig. 6, is an enlarged sectional view, showing such suction shown in Fig. 5 in position in the denture preparatory to vulcanizing said denture thereto.

40 Referring to the accompanying drawings, *a* indicates a suction disk designed for use upon an upper denture, and which comprises a disk the surface of which contacting with the palate has upon it a series of oval 45 or approximately oval projections or walls *b* *b*¹ *b*² whereby there is formed, when the denture is applied to the palate, an air chamber represented by the space *c* between the aforesaid walls *b* *b*¹ and cups represented by the spaces *c*¹ *c*² between the wall *b*¹ and the space inclosed by the wall *b*².

As will be readily understood, when the suction is applied to the denture in order

that it may conform to the outline of the surface of said denture, the said suction is given a curved outline. The bending of the suction causes the adjacent surfaces of the above mentioned walls to incline one toward the other whereby there is produced an undercut effect, and the sectional outline of the 60 spaces between the walls is of substantially dove-tailed outline. Consequently when the suction is applied to the mouth and the chambers are evacuated, the soft tissues of the palate or gums as the case may be are drawn into the dove-tailed shaped chambers and a firm adhesion of the denture secured.

The suction is produced by means of a metal mold *x* and it is partly vulcanized before application to the denture, the suctions 70 as prepared for use by the dentist having said mold *x* left thereon.

In use the suction is placed upon the mold and the denture then packed in the usual manner and then vulcanized. The metal 75 mold *x* is then removed leaving the suction embedded in and firmly adherent to the denture, the said suction, however, being of much softer rubber than the denture, whereby not only is a much better adhesion 80 obtained but the comfort of the user of the denture is considerably enhanced.

The metal cup or shield is preferably of some soft material, aluminium for example, so that it and the suction may be readily 85 bent to the desired outline.

As applied to a lower denture *d* I prefer to employ a disk of elongated outline, such as that *d*¹ shown in Figs. 2 to 6 of the drawings, in which case there is provided a 90 peripheral wall *d*² and two approximately oval additional walls *e* *e*¹ arranged with their axes upon the larger axis of the disk, forming air chambers at *f*¹ *f*² and a cup *f*³.

The application of the suction to the lower 95 denture causes the walls of the cups and chambers to incline one toward the other as previously described in connection with the upper denture.

Obviously, the outline of the disk as also 100 that of the walls and the number of the said walls may be varied as desired.

I claim:

A denture of lower teeth, formed of substantially hard material and having an im- 105 perforate-curved recessed channel portion;

suction-members of relatively softer material than the material forming the denture located on either side within the channel, and suction cups formed integral with the base of such suction-member, the back walls or bases of such suction-members being integrally perforate.

In witness whereof I have hereunto signed my name in the presence of two witnesses.

NATHAN COHEN.

Witnesses:

JOHN H. JACK,

EDMUND H. HARBERD.
